BOOKMARK

Luigi T. Marotta, Brooklyn, N. Y.

Application November 13, 1956, Serial No. 43,717

Term of patent 14 years

(Cl. D6—2)

Fig. 1

Fig. 2

Fig. 1 is a front view of a bookmark, showing my new design; and

Fig. 2 is a side view thereof.

The bottom edge of the rear fold has the same inverted V-configuration as shown on the bottom edge of the top fold in Fig. 1.

I claim:

The ornamental design for a bookmark as shown and described.
